UNITED STATES PATENT OFFICE.

GEORGE P. WIGGINTON, OF KALAMAZOO, MICHIGAN, ASSIGNOR TO KALAMAZOO LOOSE LEAF BINDER CO., OF KALAMAZOO, MICHIGAN.

SHEET BINDER.

Application filed May 28, 1925. Serial No. 33,434.

To all whom it may concern:

Be it known that I, GEORGE P. WIGGINTON, a citizen of the United States, residing at the city and county of Kalamazoo, State of Michigan, have invented certain new and useful Improvements in Sheet Binders, of which the following is a specification.

This invention relates to improvements in sheet binders.

10 In certain classes of work, for instance, county, State and other public record work, it is found convenient to make the records on loose sheets but it is also necessary that they be permanently bound to prevent tampering and for reference purposes.

It is the main object of this invention to provide a binder for record sheets and the like which may be used as a temporary binder during the preparation of sheets or assembling of a volume and as a permanent binder for such sheets.

20 A further object of this invention is to provide a binder for record sheets in which the covers may be readily renewed as occasion requires.

Objects relating to details and economies of construction and operation will definitely appear from the detailed description to follow.

30 I accomplish the objects of my invention by the devices and means described in the following specification. The invention is clearly defined and pointed out in the claims.

A structure which is a preferred embodiment of my invention is clearly illustrated in the accompanying drawing, forming a part of this invention, in which:

Fig. I is a perspective view of a binder embodying the features of my invention.

40 Fig. II is a sectional view on a line corresponding to line 2—2 of Fig. IV with the top cover open.

Fig. III is a detail view mainly in section on a line corresponding to line 3—3 of Fig. II of the permanently bound sheet body removed from the covers.

50 Fig. IV is an enlarged detail section on a line corresponding to line 4—4 of Fig. II, the binding being omitted from the covers in order to better illustrate the structural details thereof.

Fig. V is a perspective view of the post bars as employed for temporary holding of the sheets.

55 Fig. VI is a perspective view of a modified

form of post bar, both members of the coupling post being separate from the post bars and assembled therewith only when it is desired to permanently lock the sheets.

Fig. VII is a perspective view of one of the post bar coupling members coacting with the post bar coupling member shown in Fig. V.

Fig. VIII is a perspective view of the male coupling post member employed in connection with the post bars of Fig. VI.

Fig. IX is a fragmentary section on a line corresponding to line 9—9 of Fig. X of a modified embodiment of my invention, the modification being in the covers.

Fig. X is a fragmentary section on a line corresponding to line 10—10 of Fig. IX.

In the drawing similar reference characters refer to similar parts throughout the several views, and the sectional views are taken looking in the direction of the little arrows at the ends of the sectional lines.

Referring to the drawings, the covers 1 and 2, in the embodiment shown in Figs. I and II, are provided with a connecting back 3 and with a binding means comprising the clamping bars 4 hinged within the covers and having holes or sockets 5 therein.

The clamping means for the clamping bars is indicated at 6. As the details of this binding means form no part of my present invention they are not illustrated or described herein.

The sheets 7 are provided with aligned holes 8 and 9 adapted to receive the binding posts 10, the holes 8 being adapted to receive the binding posts 10 and the holes 9 being adapted to receive the coupling posts as will be hereinafter described.

The posts 10 are mounted on post bars 11 which have outwardly projecting studs 12 thereon engageable with the sockets or holes 5 in the clamping members 4 for removably securing the sheet body bound by the post bars within the covers. The posts 10 illustrated are sectional posts.

Each of the post bars 11 is provided with a coupling post member 13 having a plurality of annular grooves therein providing annular ratchet teeth 14. The opposed post bar has a hole 15 therein adapted to receive the tubular or female post member 16 which has a head 17 at its outer end to engage the bar. These post members have longitudinal slits 18 therein and a plurality of pawls 19,

the inner ends of these pawls being turned inwardly at 20 to engage the teeth 14 of the post members 13, thus providing a ratchet engagement so that when the bars, with their posts, are engaged with the sheets and the coupling post members 16 inserted and pressed down to clamp the bars firmly upon the sheets, the bars are permanently connected, the connecting means being within the sheet body so that the sheets cannot be freed without such manipulation as would destroy the binding means.

The post members 13 coact with the posts 10 for temporarily holding the sheets during the preparation of the volume or the completion of the sheets to be permanently bound.

In the modification shown in Fig. VI, each post bar 21 is provided with a pair of posts 10, the coupling post members 13' not being fixed to the post bars but being inserted through holes 22, each post bar 21 having a hole 22 at each end thereof.

In the modification shown in Figs. IX and X, the studs 23 have transverse holes 24 therein adapted to receive the locking rods 25 which are arranged through the covers 26, this means of securing the covers taking the place of the binding means 6 of Fig. II by means of which the clamping bars are clamped upon the post bar.

My improved binder is especially well adapted for the handling of public records which require permanent bindings, the law prohibiting, in many instances, of loose sheets for such public records. However, it is desirable to have means for handling the loose sheets temporarily while the volume is being compiled or the sheets collected and my improved binder provides such means.

I have illustrated and described my improvements in embodiments which I have found very practical. I have not attempted to illustrate and describe other embodiments and adaptations which might be desirable for particular records or sheets as I believe the disclosure made will enable those skilled in the art to embody or adapt my improvements as may be desired.

Having thus described my invention, what I claim as new and desire to secure by Letters Patent, is:

1. In a binder, the combination with sheets having holes adapted to receive binding and coupling posts, of covers, binding means comprising clamping bars having sockets therein, post bars provided with outwardly projecting studs engageable with said sockets and with sheet binding posts disposed in staggered relation relative to the posts of the coacting bar, said bars having coupling post members at opposite ends thereof having a plurality of annular grooves providing annular ratchet-like teeth, the bars having holes opposed

to such post members, and coacting tubular coupling post members disposed through the holes and telescoping with said toothed posts providing permanent coupling means for said post bars within the sheet body.

2. In a binder, the combination with sheets provided with holes adapted to receive binding posts, of covers provided with binding members having sockets therein, post bars provided with studs engageable with said sockets in said binding members, said post bars having sheet engaging posts thereon, and coupling posts for said post bars comprising male members on one post bar having a plurality of ratchet-like annular teeth and coacting tubular members engaging the opposed post bar and telescoping with said male members, said tubular members being longitudinally slotted providing spring pawls coacting with said teeth when said coupling post members are telescoped within the sheet body.

3. In a binder, the combination with sheets having holes adapted to receive binding and coupling posts, of covers, binding means comprising clamping bars having sockets therein, post bars provided with outwardly projecting studs engageable with said sockets and with sheet binding posts disposed in staggered relation relative to the posts of the coacting bar, and coacting coupling post members for said bars engageable within the sheet body to permanently connect the bars.

4. In a binder, the combination with sheets provided with holes adapted to receive binding posts, of covers provided with binding members having sockets therein, post bars provided with studs engageable with said sockets in said binding members, said post bars having sheet engaging posts thereon, and coupling posts for said post bars comprising coacting members engageable within the sheet body.

5. In a binder, the combination of sheets, covers, and binding bars removably engageable with said covers and provided with coacting non-releasable coupling means engageable within the sheet body for permanently securing the binding bars upon the sheet body.

6. In a binder for sheets adapted to receive binding posts, of covers, post bars provided with sheet engaging posts and with cover engaging means whereby the bars are removably secured within the covers, and non-releasable coupling means for permanently connecting said bars having co-engaging parts within the sheet body.

7. In a binder, the combination of sheets, covers, post bars provided with sheet engaging posts, said covers and post bars being provided with co-engaging means whereby the bars are removably secured

within the covers, and non-releasable coupling means for said bars comprising coacting members engageable within the sheet body whereby the bars are permanently secured upon the sheet body.

8. In a binder, the combination of sheets, covers, post bars provided with sheet engaging posts, said covers and post bars being provided with co-engaging members whereby the bars are removably secured within the covers, and non-releasable means for permanently connecting said bars.

In witness whereof I have hereunto set

my hand.

GEORGE P. WIGGINTON.
